POWER-DRIVEN CIPHERING DEVICES

Boris Caesar Wilhelm Hagelin, Zug, Switzerland

Application December 29, 1952, Serial No. 328,482

Claims priority, application Switzerland January 23, 1952

9 Claims. (Cl. 197—4)

The present invention concerns a mechanism for allowing control of power driven ciphering devices; cryptographic machines and the like by means of a keyboard similar to that of a typewriter. It is a condition that the ciphering device itself includes at least one type wheel for printing the enciphered or deciphered text. When there are more type wheels, one of them should be provided for printing the plain text set up.

A further condition precedent for the invention is that the ciphering device is power driven, preferably by an electric motor and that there is a source of current for feeding a shift control magnet.

The object of the invention is to provide a rapidly operating ciphering device of small dimensions in which the sequence of signs of the type wheel or type wheels may be arbitrarily predetermined.

By depressing a key the mechanism is caused to operate the ciphering device in such a way that the respective printing type wheel is moved to a primary position which is characterized by the fact that upon said depression of the key the sign corresponding to said key is set and prepared for printing. Following this a shifting mechanism forming part of the ciphering device is operated. As a result of this operation the type wheel is moved to another position, hereinafter referred to as a secondary position, in which the enciphered or deciphered sign is printed. The ciphering device is now ready for receiving the next sign.

In the accompanying drawing an embodiment of the invention is shown by way of example.

The numerals 100 and 101 indicate two main shafts which are both driven by power from a motor 1, shaft 100 being rotated through gearing 2 and clutch 3, and shaft 101 being rotated through gearing 2, clutch 4, shaft 110, gearing 5, shaft 111 and clutch 6. In addition, the shaft 101 may also be driven by power derived from the shifting mechanism 39 via a gearing 96. Shaft 101 supports in addition to its respective part of clutch 6, a ratchet wheel 98, a cam 36, a double type wheel 40 and a feeler arm 95. Said feeler arm is in contact with a slip ring 97 as well as a commutator 94. Said commutator is stationary mounted so as not to rotate and is the same pitch as the type wheel 40, the cam 36 and the ratchet wheel 98.

The numeral 20 indicates a key belonging to a keyboard not otherwise illustrated. Each key, as 20, of said keyboard controls a contact 18 of its own which is connected on the one hand in parallel with all of the other key contacts to the winding of an electromagnet 17, and on the other hand, via an individual one of a group of conductors 42—67 to a multiple switch 41 and thence via any of another group of conductors 68—93 to a segment of the commutator 94.

When the ciphering device is in its normal position, that is to say ready for receiving a sign, the gearing 2 is constantly rotated by the motor 1. Clutches 3 and 4 are provided in connection with said gearing 2 in order

to allow the shaft 100 and the shaft 110 of the gearing 5, respectively, to be released from gearing 2 and thus also from the motor. When thus released shaft 100 and gearing 5 stop rotating and are, furthermore, immediately locked in their positions, the former at the ratchet wheel 98 by the action of a pawl 29 and the latter at the ratchet wheel 7 by the action of a pawl 8. Pawl 29 is biased by a spring 34 and pawl 8 is biased by a spring 9, both of said springs tending to bring the respective pawls into engagement with their ratchet wheels.

As an alternative, the gearing 5 when in normal position may be left unlocked by the locking device 7, 8.

The electromagnet 17 is energized when the cam operated contact 37 is closed as well as when the feeler arm 95 is in contact with a segment of the commutator 94 which is connected via one of the conductors 68—93, the multiple switch 41 and one of the conductors 42—67, with the closed key contact 18 which closes the circuit through the winding of magnet 17. Here it should be noted that in the normal position of the ciphering device all of the key contacts are held closed. Consequently, the electromagnet 17 holds its armature 14 constantly attracted in the normal state of the device. This is also the case as long as the shaft 101 rotates constantly as above mentioned. The cam operated contact 37 is opened momentarily by the action of cam 36 each time the feeler arm 95 is in the middle of a segment of commutator 94.

When a key 20 is depressed its offset 22 is caught by the tooth 23 of a lever 21 after said lever has first been moved to the left by the sloping edge of the key below offset 22. At this movement a fork 102 engaged by said lever 21 is moved to the left together with the bar 10 carrying same, thereby allowing the hook-shaped left hand end of bar 10 to drop behind the angularly bent upper end of pawl 8. As soon as the offset 22 passes the tip of tooth 23, a spring 11 biases the lever 21 to the right until a full engagement is established between 22 and 23. By this movement of lever 21 the fork 102 as well as its supporting bar 10 is accordingly moved to the right, the bar in its turn moving the upper end of pawl 8 to the right, thereby disengaging pawl 8 from ratchet wheel 7. This will release gearing 5 and shaft 101. Here it may be noted that the key 20 when depressed locks, by means not shown, all of the other keys of the keyboard against operation.

Shaft 101 when thus released starts rotating and continues to rotate until the feeler arm 95 comes into contact with a segment of the commutator 94 which is connected via the multiple switch 41 to the key contact 18 held open by the depressed key. At the same instant when the cam operated contact 37 is opened, the electromagnet 17 is de-energized allowing its armature 14 to drop; which starts the following operations:

(a) The projection 24 of the depending arm 15 of armature 14, biased as it is by spring 16, locks the ratchet wheel 98 of shaft 101 against rotation. The type wheel 40 is now in its primary position in which the sign corresponding to the key depressed may be printed. The multiple switch 41 allows predetermining any distribution desired of the signs on the type wheel 40. To this end it is only necessary to set the multiple switch 41 to such a position that upon depression of any desired key of the keyboard the proper primary position corresponding to said key is obtained.

(b) The armature 14 acts on the back 13 of bar 10 without displacing the latter longitudinally. The resulting swinging movement of the bar on pivot 99 against the action of its biasing spring 12, releases pawl 8 which under the influence of its spring 9 engages the ratchet wheel 7 and locks it against rotation thereby also lock-

ing the gearing 5 and releasing it at clutch 6 from shaft 101.

(c) The detent 25 formed by the hooked lower end of arm 15 releases ratchet wheel 26. Shaft 100 starts rotation and transmits said rotation to the shifting mechanism 39. As soon as shaft 100 starts rotation, cam 27 restores the armature 14 to normal position, thereby causing its depending arm 15 again to release shaft 101. The shifting mechanism 39 imparts via gearing 96 to shaft 101 a number of ciphering steps which depends on the intrinsic setting of mechanism 39 with a resulting rotation of the type wheel 40 to its secondary position in which the enciphered (or deciphered) sign may be printed. The clutch 6 releases shaft 101 from the locked gearing 5.

Immediately before shaft 100 has completed a revolution the cam 28 forces the pawl 29 to the side, thereby swinging the lever 30 against the action of spring 34. Lever 30 displaces by means of its upper hooked end 35 the bar 16 another time to the left, yet without causing it to engage pawl 8 by its left hand end, that is to say, the bar only slides at 99. Lever 21 which is caused to partake in this movement releases at 23, 22 the depressed key 20. Springs 34 and 11 restore the respective levers 30 and 21 to normal position. As, however, by that time armature 14 and its depending arm 15 is in its normal position, cam 26 is again locked by the detent 25, thereby in its turn locking the shaft 100 against rotation. The cycle of operation is now ended, and the ciphering device is restored to normal position ready for receiving another sign.

I claim:

1. In a ciphering device, the combination of a keyboard having keys for setting up sequences of signs to be enciphered or deciphered, at least one type wheel for reproducing enciphered or deciphered sign sequences, electric means under the control of the keys of said keyboard for setting the type wheel in a primary position in response to the key operated, a rotatable shaft for supporting the type wheel, solenoid means for instantly arresting said shaft and locking it against rotation at the attainment of said primary position, and means controlled by said solenoid means for shifting the position of the type wheel from said primary position to a secondary position for modifying the sign sequences said electric means comprising a stationary commutator and an associated contact member mounted for movement with said rotatable shaft for supporting a type wheel.

2. In a ciphering device, the combination with a type wheel for reproducing enciphered or deciphered sequences of signs, a shaft for supporting said wheel, power driven means and magnetic arresting means for setting said shaft with the type wheel in a primary position, an electric circuit system for controlling said setting operation, said electric circuit system including a group of key-controlled contacts, a commutator-selector having a corresponding group of contacts in combination with said shaft, a multiple switch inserted between said group of key-contacts and said selector for connecting any desired key-contact with any desired selector contact, and a shifting mechanism controlled by said electric circuit system for moving said shaft with the type wheel from said primary position to a secondary position.

3. In a ciphering device as claimed in claim 2 the further feature that the said multiple switch is provided with fixedly interlinked, exchangeable switch elements for operatively associating any given type wheel with a switch element controlling a selected sequence of signs corresponding to that of the type wheel.

4. In a ciphering device as claimed in claim 1 at least one of said type wheels being exchangeable.

5. The combination with a ciphering device having a type wheel and a shaft therefor for setting the type wheel in a primary position, in which it may reproduce a sign to be enciphered or deciphered, and a shifting mechanism

with a shaft therefor for moving the type wheel into a secondary position after each primary setting thereof, of a set of keys for setting up signs to be enciphered or deciphered, a power motor, transmission means for imparting rotation from said motor to said shafts, mechanical means under the control of the keys for coupling the type wheel shaft to said transmission means upon the depression of a key, means for stopping the rotation of the type wheel shaft, an electric circuit for controlling the operation of said stopping means, a contact at each key for preparing said circuit for a stopping action on the depression of a key, a selector comprising a stationary commutator and an associated movable contact controlled by the type wheel shaft for causing the circuit to effect stopping of the type wheel shaft, when the type wheel reaches its respective primary position, and means operable by said circuit for connecting the shaft of the shifting mechanism to the power transmission means for rotating the shifting mechanism and causing it to move the type wheel shaft with the type wheel to the secondary position immediately after the type wheel has stopped in the primary position.

6. In a ciphering device, the combination of a keyboard having keys for setting up signs to be enciphered or deciphered, a type wheel for reproducing one at a time the signs thus set up, a shaft for supporting said type wheel, a motor, means for transmitting power from the motor to the type wheel shaft, an electric circuit including a key-operated contact, a selector contact connected to the type wheel shaft for rotation thereby, a stationary commutator for cooperation with said selector contact, an electromagnet operable under the joint control of said contacts, and means operable by said electromagnet for arresting the type wheel in a primary position, a shifting mechanism for moving the type wheel shaft from said primary position to a secondary position, and means under the control of said electromagnet for imparting a rotation from the motor to the shifting mechanism for causing it to effect said movement of the type wheel to a secondary position.

7. In a ciphering device, the combination with a type wheel for reproducing enciphered or deciphered signs, a shaft for supporting said type wheel, a shifting mechanism, a shaft therefor, a motor, transmission means for imparting power from said motor to said shafts, a set of keys, mechanical means operable by the depression of a key for coupling the type wheel shaft to the power transmission means for rotating said type wheel shaft, an electric circuit system for stopping said rotation of the type wheel shaft, when the type wheel has reached a primary position corresponding to the key depressed, said electric circuit system comprising an electromagnet, a group of key-controlled contacts, a selector comprising a stationary commutator having a corresponding group of contacts and a movable contact for cooperation therewith, said contact being connected to the type wheel shaft for moving therewith, a multiple switch inserted between said group of key-contacts and said commutator contacts for connecting any desired key-contact with any desired commutator contact, a shifting mechanism for moving the type wheel shaft from said primary position to a secondary position and means under the control of said circuit system for coupling the shifting mechanism to the power transmission means for causing the shifting mechanism to effect said operation of the type wheel shaft.

8. In a ciphering device, the combination of a group of keys for setting up signs to be enciphered or deciphered, a type means for reproducing respectively the signs set up by said group of keys, a shaft for supporting said type means, a motor, means for transmitting power from the motor to the shaft, an electric circuit including a key-operated contact, a selector means connected to said shaft for rotation thereby, distribution means for cooperation with said selector means, an electromagnet operable under the joint control of said contact and said selector means, a

bell crank having one arm thereof constituting an armature for said electromagnet and having its other arm provided with a cam follower means on its end and a projection intermediate the cam follower means and the pivot of said bell crank for arresting the type means in a first position in response to movement of said bell crank from a normal position upon de-energization of said electromagnet, a mechanism for moving said type means to a second position, and means for actuating said mechanism for causing it to effect said movement of said type means to said second position and having cam means connected thereto arranged to act on said cam follower means and to restore said bell crank to said normal position.

9. The combination set forth in claim 8, said means for actuating said mechanism being under the control of said electromagnet.
